US00D494867S1

(12) **United States Design Patent** (10) Patent No.: **US D494,867 S**
(45) Date of Patent: **** Aug. 24, 2004**

(54) **STACKABLE LOW DEPTH TRAY**

(75) Inventor: **William P. Apps**, Alpharetta, GA (US)

(73) Assignee: **Rehrig Pacific Company**, Los Angeles, CA (US)

(**) Term: **14 Years**

(21) Appl. No.: **29/171,391**

(22) Filed: **Oct. 21, 2002**

3,055,531 A 9/1962 Chelbor
3,055,542 A 9/1962 Russo
3,092,284 A 6/1963 Stout

(57) **CLAIM**

The ornamental design for a stackable low depth tray, as shown and described.

DESCRIPTION

FIG. 1 is a perspective view of the stackable low depth tray according to the present invention;

FIG. 2 is a top plan view of the tray of FIG. 1;

FIG. 3 is a bottom plan view of the tray of FIG. 1;

FIG. 4 is a front side elevational view of the tray of FIG. 1, the rear side elevational view being a mirror image thereof; and,

FIG. 5 is a right side elevational view of the tray of FIG. 1, the left side elevational view being a mirror image thereof. The broken lines shown are for environmental purposes only and are not part of the claimed design.

1 Claim, 5 Drawing Sheets
